OF NEW YORK, N. Y.

MECHANISM FOR CONTROLLING CARBONS OF ARC-LAMPS.

1,271,162.

Specification of Letters Patent.

Patented July 2, 1918.

Application filed February 25, 1916. Serial No. 80,474.

To all whom it may concern:

Be it known that I, ARTHUR WILLIAM HARRIS, a subject of the King of Great Britain, residing at 38 Joffray road, Erdington, in the county of Warwickshire, England, have invented certain new and useful Improvements in Mechanism for Controlling Carbons of Arc-Lamps, of which the following is a specification.

10 The invention concerns the automatic feeding of carbons of arc lamps and it consists in the features and combination and arrangement of parts hereinafter described and particularly pointed out in the claims.

15 In the drawings:

Figure I is a side view of the immediate operating mechanism for the carbons.

Fig. II is a view of Fig. I a quarter turn therefrom.

20 Fig. III is a diagrammatic view of the apparatus with the wiring.

Fig. IV is a side view of a solenoid and associated parts looking from the right of the corresponding parts in Fig. III.

25 Fig. V is a side view of a relay and associated parts looking from the right of the corresponding parts in Fig. III.

Fig. VI is a view of another form of relay that may be used.

30 Fig. VII is a view of a brush or sliding circuit closer.

In these drawings —a— Figs. I and II is the shaft of the immediate carbon feed mechanism. This may be of any desired 35 form and constitutes no part of my invention. This shaft is provided with a handle *b* by which it may be manually operated in either direction. On this shaft is mounted a ratchet wheel *c*, and an arm *d* is also 40 mounted on this shaft, though loosely. This arm carries a pawl *e* pivoted thereto at *f* and adapted to engage the ratchet wheel. The pawl is normally out of engagement with said ratchet wheel, so that the adjustment of the carbons can be accomplished at 45 any time and in either direction by simply turning the hand wheel manually. The pawl is made to operate the ratchet wheel by a rod *g* connected to said pawl and also 50 connected with the armature of the solenoid 14, which armature is normally lifted by a spring 14^a. When the solenoid coil is energized and its armature is thereby pulled down, the first effect will be to tip the pawl 55 into engagement with the ratchet wheel and

then the further draft of the rod will turn the ratchet itself and thus feed the carbons.

As before stated, the operating rod *g* is connected to the pawl directly instead of to the arm which carries the pawl, so that 60 the pawl will be normally out of contact with the ratchet wheel and will be thrown into engagement therewith as the first effect of the operation of the rod *g*. To insure this action, the pivoted pawl carrying 65 arm *d* is provided with retarding or restraining means which may be of various forms, but in the particular construction shown it consists of an arm *h* suitably mounted on the casing and slotted to receive 70 a screw or bolt *h'* carrying a friction washer *h²*, the tension of which may be regulated by the screw. This screw is carried by the pawl arm *d* and when the pawl arm moves it must carry the friction washer 75 with it. The arm is thus under restraint to this extent, and this insures that the first effect of the pull of the rod *g* will be to tip the pawl into engagement with the ratchet and after this has taken place, the further 80 movement of the rod *g* will turn the pawl and its arm and thus turn the ratchet to feed the carbons. The normal position of the pawl is determined by the stop *h³* secured to the pawl arm *d* and the upward 85 position of the pawl carrying arm is determined by the bolt or screw *h'* coming against the upper wall of the slot.

The solenoid 14 is in a high tension circuit shown in Fig. III which may be traced 90 as follows:

Line 17, fuse 17^a, knife switch contacts 10, 11, line 18 to solenoid 14, and line 19, fuse 19^a, line 20, it being understood that contacts 10, 11, must be closed by the bridge 95 or knife switch member 9 in order that this high tension circuit be completed. The bridge or knife switch contact 9 is carried by but insulated from a slide 21, suitably guided and connected with the armature 7^a of 100 the solenoid 7. The solenoid coil is in a branch of a shunt circuit controlled by the relay, the armature of which is shown at 3, its coil or coils at 3^a and its contact co-operating with the armature at 4. The armature 105 is under tension of spring 6, tending to move it against the said contact 4, whereas the pull of the magnet or magnets will break contact at 4. The relay magnet is in the shunt circuit mentioned which leads off 110

from the resistance box X, in the main high tension arc circuit, leading to the carbons, which are indicated at y, w, and this shunt circuit also includes a resistance 5 and contacts 12 and 13 for cutting out said resistance when the knife switch or bridge No. 8 controlled by solenoid 7 contacts therewith, all as will be described hereinafter.

The shunt circuit may be traced as follows:

Line 1, fuse 23, lines 24 and 25 to resistance coil 5, line 26 to relay magnet or coil, thence by line 27, fuse 28 and line 29 back to the resistance box. This shunt circuit is so connected with the plates of the resistance box as to supply a current of say 10 volts, the high tension current being say 110 volts.

The branch of this shunt circuit which controls the switch solenoid 7 may be traced as follows:

Line 24^a to contact 4 of the relay armature or switch arm 3, line 30 to solenoid 7, line 31 from solenoid to lines 27 and 29 of the main shunt circuit.

In addition to the circuits and devices above described, I provide a circuit 40, 41, which is in multiple with the branch shunt circuit which includes the solenoid coil 7, and this circuit 40, 41 includes a supplemental relay magnet 32 which, therefore, is energized simultaneously with the solenoid coil 7. This relay controls contacts 3^x, 4^x, in a local circuit as follows: wires 24, 38, fixed contacts 36 and 35 (when closed by the brush contact 37, which is attached to the sliding member 21), wire 34 to armature 3^x of the magnet 32 (which armature is held normally away from contact 4^x by spring 39), contact 4^x, wires 33—30, coil 7 and wires 31, 27 and 29. The relation of the brush 37 to the contacts 36 and 35 is such that contact will be closed at 36 and 35 before the contact arm 8 bridges contacts 12 and 13 and cuts out the resistance 5, and the length of the contacts 36 and 35 is such, relative to the movement of the slide 21, that brush 37, after closing the circuit at the contacts 36, 35, will break said circuit at the final part of the movement of the slide 21, that is the final part of its upward movement in the diagram, Fig. 3, and this breaking of the local circuit at 36, 35, will take place while the arm 8 is still bridging the contacts 12 and 13 and is still cutting out the resistance 5, and, therefore, while the circuit remains broken at 3, 4. It will be observed, however, that the circuit which includes the contacts 3^x, 4^x, and the solenoid coil 7, when established, will be maintained independently of the contacts 3 and 4 or, in other words, the energizing of the solenoid coil 7 having been effected or initiated by the closing of the contacts at 3, 4, the coil 7 will still be energized through the local circuit

of which the contacts 3^x, 4^x, form a part after the circuit controlled by contacts 3 and 4 is broken.

One specific object of the invention is to control the feed of carbons in an arc lamp of moving picture machines, which service requires an evenness of feed not called for in ordinary service such as street lighting.

As before stated, I extend a pair of shunt leads from the arc resistance box X and deliver thereto a ten volt current to the coils 3^a of the relay by way of the resistance 5 which, as stated, is in series with the relay coils and provides a resistance of about 30 ohms. The relay controls the energizing of supplemental relay 32 and solenoid coil 7, which latter controls the knife switches 8, 12 and 13 and 9, 10, 11. The effect of this combination of elements, referring more particularly now to coil 3 and solenoid 7 and the contacts 8, 12 and 13 and 9, 10 and 11, is that when the arc light is consuming the required amount of current to illuminate the picture, the strength of the current shunted to the coil 3^a of the relay is such that the magnetic field created is strong enough to retain the armature 3 resting on the pole piece 3^c, or rather on the rubber pad 3^b, with which said pole piece is tipped. This holding effect of the armature 3 by the magnet is in opposition to the pull of the spring 6, and in this position of the armature, *i. e.*, against the magnet pole, the local circuit or branch controlled by the relay and leading to the solenoid 7 is open and the switches 8 and 9 are held down or opened by the spring 15. As the current consumed by the arc lamp decreases, owing to the burning away of the carbons, the strength of the current shunted through the relay coil decreases proportionately until a point is reached where the magnetic field is not strong enough to counter-balance the pull of the spring 6, on the relay armature, hence the armature 3 is pulled away from the pole piece until it rests on the contact at 4. This closes the local circuit described to the solenoid type of magnet 7, so that the shunt current is now also fed to this coil energizing it and causing its armature to travel toward its core, carrying with it the two insulating bridging arms 8 and 9. This movement of the solenoid armature 7^a is timed or regulated by any suitable form of dash pot, such as is shown at 7^x. Bridge 9, in the course of its travel, first bridges contacts 10 and 11, these being longer than contacts 12 and 13, and near the end of the travel of the armature 7^a bridge piece on knife switch 8 closes contacts 12 and 13. When contacts 10 and 11 are closed, the main line current of 110 volts is carried to the solenoid magnet 14 through the circuits 18, 19, 20 described, which solenoid it energizes, thereby causing its armature to travel and causing its pawl to en-

gage the ratchet wheel permanently fixed to the feeding shaft *a* of the arc lamp. This ratchet wheel is revolved by the travel of the armature to relatively move the arc carbons so that the current consumption is increased and hence the strength of the shunt current is also increased.

Near the completion of the stroke of the armature 7^a of solenoid 7, and after the current has been supplied to solenoid 14 for feeding the carbons, the insulated bridge arm 8 closes the contacts 12 and 13 so that the resistance 5, which is in series with the relay coil 3^a is bridged or cut out, allowing the full strength of the shunt current to energize the relay coil. The strength of the magnetic field of this coil is thereby so greatly increased that the armature 3 is drawn back to its original position resting on the core of the relay magnet, thus breaking contact at 4 and hence the supply of the shunt current to coil 7 is discontinued.

It is desirable to maintain the coil 7 in action after being energized by the closing 25 of the contacts at 3, 4, and after said contacts have been opened by the cutting out of the resistance 5, as stated, in order to secure a continuous one movement feed of the carbons, and to this end I provide the supplemental relay 32, and sliding brush contact 37 and contacts 35, 36 and circuit connection to maintain coil 7 in circuit independently of the contacts at 3, 4 controlled by the relay magnet 3.

35 When, therefore, the solenoid 7 is energized by the closing of the branch shunt circuit at 3, 4, the coil of supplemental relay is energized simultaneously and the contacts 3^x, 4^x are closed. The upward movement of the 40 slide 21, due to the sucking action of coil 7, also brings the brush contact 37 to bear and slide upon the elongated contact strips 35 and 36. This completes the circuit of which the contacts 3^x, 4^x, form a part and which 45 includes the coil 7 maintaining it energized, namely, wires 24, 38, contacts 36, 37, 35, wire 34, armature 3^x, contact 4^x, wires 33, 30, coil 7, wires 31 and 27, 29. After this circuit is 50 established the switch arm 8, due to the continued upward movement of the slide 21, engages contacts 12 and 13, cutting out resistance coil 5 and thus enabling magnet 3 to open the contacts 3 and 4. During this action, and continuing after it, the brush 37 55 still slides on the contacts 35 and 36, and, as stated above, the energizing of the coil 7 is maintained independent of the contacts 3, 4, allowing the armature 3 to assume a position of rest against the magnet poles. The coil 60 7 will be maintained in action, continuously drawing up the slide 21, and maintaining the high tension circuit to the magnet or solenoid 14 until the brush contact 37 moves above and out of engagement with the contacts 36, 35, whereupon the local circuit,

which includes the supplemental relay contacts 3^x, 4^x, will be broken and the coil 7, therefore, will be deenergized, allowing the spring 15 to draw the slide 21 down again. The branch shunt circuit 30, 31, will remain 70 broken at 3, 4 by the armature 3 remaining at rest and against the poles of magnet 3 and the supplemental relay magnet 32 will be deenergized simultaneously with that of coil 7 and the local circuit will be broken at 3^x, 75 4^x, and the apparatus therefor will be restored to its normal condition for a new operation.

The armature carrying the bridge pieces 8 and 9 is now drawn down by its spring 15 80 to its normal position, breaking this circuit to the coil 14 and leaving the resistance 5 again in series with the relay coil.

It follows that to vary the consumption of current by the arc, it is only necessary to 85 vary the strength of the spring 6 of the relay 3, 4, by means of its adjustment screw. If the pull of the spring 6 is increased, the magnetic field of the relay coil will have to be correspondingly stronger in order to retain the armature 3 on its pole piece, hence the normal consumption of the arc lamp will have to be correspondingly greater, so that the shunt current may also be increased to 90 the required strength. 95

The apparatus shown in Fig. III may be used in the position there illustrated, or in reversed position.

The lamp mechanism may be of any well known type, such as that made by the Standard Moving Picture Co., The Precision "Simplex" Machine Co., Inc., the Nicholas Power Co., the Goumont Company of Paris, France, or it may be of the hand feed type shown in the patent of Roebuck, No. 105 1,120,086, December 8th, 1914.

I claim as my invention:—

1. In combination with the carbon feeding mechanism of an arc lamp for motion picture machines, controlling means therefor, comprising a magnetic relay, the coil of which is in a shunt circuit from the arc lamp circuit, a resistance in said shunt circuit in series with the coil of said relay, electromagnetic means controlling a high tension 110 circuit to the carbon feeding mechanism, said electromagnetic mechanism including a circuit closer for said high tension circuit, and a cut-out for said resistance, to effect a temporary increase in the strength of the 115 magnetic field of the relay, and a branch shunt circuit for energizing the said electromagnetic high tension circuit closer controlled by the said relay, substantially as described. 120 125

2. In combination with the carbon feeding mechanism of an arc lamp, an electromagnetic switch controlling circuit connections leading thereto, an electromagnetic relay in a shunt from the main arc circuit and 130

- controlling a circuit leading to said switch, a resistance in said shunt circuit in series with the said relay, and means for cutting out said resistance when the high tension 5 switch is operated to close its circuit to the carbon operating mechanism, to thereby cause the relay to operate and cut out the high tension switch which then is restored to open position, substantially as described.
- 10 3. In combination, electromagnetic carbon operating means, a timed electromagnetic switch, controlling the circuit to said electromagnetic carbon operating means, a shunt circuit, an electric magnetic relay in said 15 shunt circuit controlling a branch circuit to the said timed electromagnetic switch, and a resistance in said shunt circuit and in series with the relay, and means for cutting out said resistance when the carbons per-
- 20 form a feeding movement, to thereby increase the strength of the magnetic field of the relay in said shunt circuit, to permit the same to resume its normal condition, said resistance then being cut into the circuit, sub- 25 stantially as described.
4. In combination, carbon feeding means including an electromagnetic member, a switch controlling the circuit thereto, electromagnetic means for controlling said 30 switch, a shunt circuit for said electromagnetic switch, controlling means comprising a relay for making or breaking said shunt circuit leading to said switch controlling means, a resistance in the shunt circuit with 35 the said relay and in series therewith, a cut-out switch for said resistance operating after the closing of the switch first mentioned, substantially as described.
5. In combination, carbon operating means, 40 a relay in a shunt circuit from the main arc lamp circuit, an electromagnetic switch controlling a circuit to the carbon operating means, said electromagnetic switch being in a local circuit controlled by the relay, and 45 means for momentarily increasing the strength of the relay magnet to throw the switch to open position, said means being controlled by the said electromagnetic switch, substantially as described.
- 50 6. In combination, electromagnetic carbon feeding means, a relay in a shunt circuit from the main arc lamp circuit, a resistance in said shunt circuit and in series with the relay coil, an electromagnetic switch consist- 55 ing of a solenoid coil in a local circuit controlled by the relay, a reciprocating carrier connected with the solenoid armature, a knife switch member on said carrier, contacts closed by said knife switch member, a 60 circuit including said contacts and the electromagnetic carbon operating means, a second knife switch member on said carrier, a pair of contacts to be closed by said second knife switch member for cutting out the 65 resistance coil, said carrier operating to open the switches when the solenoid coil is deenergized, substantially as described.
7. In combination with the carbon feeding mechanism of an arc lamp for motion picture machines, controlling means there- 70 for, comprising a magnetic relay, the coil of which is in a shunt circuit from the arc lamp circuit, a resistance in said shunt circuit in series with the coil of said relay, electromagnetic means controlling a high 75 tension circuit to the carbon feeding mechanism, said electromagnetic mechanism including a circuit closer for said high tension circuit, and a cut-out for said resistance, to effect a temporary increase in the strength 80 of the magnetic field of the relay, and a branch shunt circuit for energizing the said electromagnetic high tension circuit closer controlled by the said relay, a supplemental 85 relay energized simultaneously with the said electromagnetic means of the high tension circuit closer, and closing a contact in a local circuit to said electromagnetic means, and a second circuit closer in said local circuit controlled by said electromagnetic 90 means to maintain the same in circuit after the resistance is cut out and the shunt circuit is broken at the main relay, substan- tially as described.
8. In combination with the carbon feeding mechanism of an arc lamp, an electromagnetic switch controlling circuit connections leading thereto, a main electromagnetic relay in a shunt from the main arc circuit and controlling a circuit leading to 95 said electromagnetic switch, a supplemental relay in multiple with the electromagnetic switch and energized simultaneously therewith, said supplemental relay controlling a contact in a branch or local circuit which 100 includes said electromagnetic switch, a second contact in said branch or local circuit which is controlled by the electromagnetic switch itself, said electromagnetic switch being initially energized through the main relay and thereafter maintained in service by the closing of the local circuit by the supplemental relay and the said second contact and independent of the contacts controlled 105 by the main relay, means for reducing the 110 resistance in the shunt circuit which includes the main relay, said means being operated by the said electromagnetic switch and thereby causing the main relay to break the branch shunt circuit, the said second 115 contact in the local circuit being thereafter broken by the continued movement of the electromagnetic switch, whereupon said switch and the supplemental relay are 120 restored to normal position, substantially as 125 described.
9. In combination with the carbon feeding mechanism of an arc lamp, an electromagnetic switch controlling the circuit thereto, and consisting of a solenoid, the 130

armature of which closes a contact in said circuit, a main relay in a shunt from the main arc circuit controlling the initial energizing of the solenoid, a supplemental relay 5 in multiple with the solenoid, and controlling a circuit closer in a local circuit which includes said solenoid, a second contact in said local circuit controlled by the movement of the solenoid armature and operating with the contact at the supplemental relay to maintain the solenoid energized after the main relay is out of service and until the solenoid armature has performed a prescribed movement, after which the local

circuit is broken and the solenoid armature 15 is restored to normal position and means for cutting out resistance in the shunt circuit which includes the main relay while the solenoid remains energized through the local circuit, to thereby break the circuit to 20 the solenoid, substantially as described.

In testimony whereof I affix my signature in presence of two witnesses.
